Bean & Skinner,

Fire Place.

Patented June 12, 1835.

June 12-1835

Ira. J. Bean and Elijah Skinner's fire place.
Letters Patent.

The Schedule referred to in these Letters Patent and making part of the same containing a description in the words of the said Ira Bean and Elijah Skinner themselves of their improvement in the common fire place

to all to whom these Presents shall come

We it know that we Ira Bean and Elijah Skinner of Sandwich in the County of Strafford (our State of New Hampshire) have invented a new and useful improvement in the common fire place and that the following is a full and exact description of the construction of said improvement, as aforesaid. In the hearth of a common fire place we make a box of iron work or cast iron about eight inches deep, (and equal in length to the width of the back of the fire place) and extending outward from the back eight inches further than the jambs or (cooking) We then cover this box in part with a horizontal cast iron plate made level with the top of the hearth, with a ledge on the back edge, (and) extending inward so far as to leave an open space between this and the back of the fire place sufficient to receive the false back herein after described. We then attach to the top of the back edge of this cover a perpendicular wall iron plate about eight or ten inches high (and upon the top of this we place horizontally another cast iron plate with a ledge upon the back edge, and) wide enough to cover the whole opening left for the false back except a sufficient place for a flue in the back of the fire place. And in this cover or plate we make openings to receive boilers of different sizes with covers to the openings as in cooking stoves. We then place suspended directly upon the back edge of the cover of the false back a plate of sheet or cast iron extending upward far enough (and at a proper distance from the back of the fire place) to form a sufficient flue to conduct the smoke into the throat of the chimney. We then make the ends of the false back of iron work or cast iron so as to make a neat finish for an open fire place, (and when we wish to use it as such, we extend the front of the false back upward of necessary by a plate of sheet iron any required height. We also make in the cover of the box in the hearth a door

near the front to receive the fuel, with a small aperture in the door to give the necessary draught. We have a small east iron flue leading from in, or both ends of the box, (and out through the hearth at or near the corner of the chimney, so constructed as to receive funnels to convey the heat more directly into to the room when necessary), (and in the flue in the back) ^{before} (and in the funnels we have dampers to regulate the heat. We use the box in the hearth, and the flues (and funnels without any false back) if we choose so to do, or we use the false back with the back flue, without the funnels or box in the hearth in which case we have an opening in the front of the false back to put in the fuel. What we claim as new and our invention or improvement, is the construction of the box in the hearth, and the arrangement and application of the same with the flues, funnels (and false back), to common open fire places. The object of which is to save room (and fuel), furnish a cheap and convenient apparatus for cooking (and at the same time avoid the impure air, occasioned by) close stoves, and the steam from cooking stoves. Sandwich Nov 1. 1834.
